Berney G. Barr
ATTORNEY

UNITED STATES PATENT OFFICE.

WILLIAM J. DIEDERICHS, OF MANSFIELD, OHIO, ASSIGNOR TO WESTINGHOUSE ELECTRIC & MANUFACTURING COMPANY, A CORPORATION OF PENNSYLVANIA.

ANNEALING FURNACE.

Application filed November 7, 1927. Serial No. 231,489.

My invention relates to furnaces and more particularly to furnaces adapted for annealing operations.

In bright annealing operations, the work to be annealed is placed in a gas-tight container and if necessary or desirable a suitable non-oxidizing atmosphere is maintained therein. A removable furnace casing or bell consisting of refractory heat insulating material, surrounds the container, and electric heating elements are supported either upon the inner wall of the furnace casing or upon the walls of the gas-tight container. Difficulty has been experienced in quickly and efficiently heating the work and at the same time maintaining a proper heat distribution within the container.

It is an object of the present invention, therefore, to provide an annealing furnace whereby the work to be heated and the heating elements are so positioned within a gas-tight chamber that a circulation of the atmosphere therein is set up past the heater and around the work, whereby a rapid and uniform heating of the work is effected.

In practicing my invention I stack the work to be heated substantially in the shape of a chimney and mount a resistance heating element within the space defined thereby. The work and resistor are surrounded by a hood and means are provided whereby a gas of desired chemical characteristics is permitted to circulate past the heater, through the stack, and down around the outer surface thereof.

In the drawings the single figure is a view in vertical section of an annealing furnace embodying my invention.

Referring more particularly to the drawings, a furnace embodying my invention comprises a cylindrical furnace casing 2 and roof 4 of suitable refractory heat-insulating material enclosed by a metallic shell 6. The shell completely covers the outer surface of the refractory casing and is provided at the lower peripheral rim thereof with an annular flange 8 adapted to extend beneath the refractory portion 2 in supporting relation.

Eye-bolts 10 are secured to the upper peripheral rim of the metallic shell 6, and are adapted to be engaged by crane-hooks or other suitable means to facilitate the handling of the furnace casing.

The furnace casing is adapted to be supported in operative position upon a base of suitable refractory material having conduits 12 and 14 extending therethrough within the area defined by the casing, as hereinafter described.

Sinuously wound electrical resistance elements 16 are supported upon the inner face of the refractory wall 2 by means of suitable supports and spacers 18, in a well known manner.

Since the particular details of construction of the furnace casing form no part of the present invention, further description thereof is not deemed necessary.

Within the chamber defined by the casing 2, when in operative position, and substantially co-axial therewith, is a circular plate 20 mounted upon the refractory base and apertured to receive the terminals of the conduits 12 and 14. An annular channel 22 is formed adjacent to the periphery of the plate 20 and is filled with a granular refractory material such as sand.

A bell or container 24, of low heat-storage capacity and co-extensive in diameter with the mean diameter of the channel 22, is positioned within said casing with the lower peripheral edge thereof resting in the granular material in the channel 22 to form a sand seal in a well known manner. Although a sand seal does not constitute a perfect hermetic seal for the container, the flow of air or gas therethrough is reduced to such a point that the container is substantially gas-tight.

An eye-bolt 26 is secured to the top of the container 24 to facilitate the movement thereof during the charging and discharging operations, as hereinafter described.

The work to be annealed comprises, in the present embodiment, circular coils of wire or steel strip 28, supported upon a spider 29 which is mounted upon the plate 20 in co-axial relation therewith.

The main heating element comprises a resistance wire 30 wound to form a double helix and is maintained in operative relation by a plurality of apertured blocks 32, of refractory electric-insulating material. The electrical connections (not shown) for the heating elements are effected in the usual manner.

Between the heating element 30 and the

work 28 and supported upon the base plate 20 is positioned a cylindrical grid 34 which effectively prevents engagement between the work being heated and the heating elements.

5 A suitable non-oxidizing gas may be forced into the container through the conduit 12 and escapes therefrom through the conduit 14 to maintain a chemically neutral atmosphere within the container and to thereby prevent 10 surface oxidization of the material being heated. The gas employed depends upon the final character of the surface desired, so that the gas may or may not be non-oxidizing. On the other hand, in many operations, the 15 use of a gas may be dispensed with, in which event the conduits 12 and 14 are closed.

In operation, the furnace casing 4 is raised and removed, the container 24 is removed, and the work to be heated is stacked upon 20 the spider 30 substantially in the shape shown. The container 24 is then replaced in operative position with the lower edge thereof resting in the sand containing channel 22 and the furnace casing 4 is lowered into 25 operative relation therewith.

Upon energization of the heating element 30, it is clear from the drawing that the portions of the work constituting the inner surface of the chimney are heated directly by 30 radiation thereby, and, as the atmosphere within the stack becomes heated, a circulation is set up as indicated by the arrows, whereby the heat is convected down around the outer surface of the stack to materially 35 increase the rate of heating thereof.

In addition, if a gas or desired chemical characteristic is introduced through the conduit 12, a circulation will be set up as indicated by the arrows in the drawing, resulting in a more uniform effect of the gas upon 40 the material being heated, and, by continuously convecting heat about the material, more uniform heat distribution within the container is effected. The heating elements 45 16 carried by the furnace casing 4 may be energized if a relatively high temperature is desired.

When the heating operation has been completed, the furnace casing 4 is raised and removed to permit the work to cool. Since 50 the container 24 is of relatively low heat storage capacity, the cooling in air will be relatively rapid and, during the cooling operation, the work is kept out of contact 55 with the air, and the non-oxidizing atmosphere, if used, may be maintained in the container.

Clearly, many changes may be made in the details of construction as described and be 60 within the scope of the present invention. For example, the form of the heating element 30 may be altered, as desired, and the particular means for sealing the container against the influx of air may be varied, de-

pending upon the temperature added there- 65 in. Also, while I have shown the material to be annealed as constituting coils of wire or strip metal, quite clearly any charge may be heated which can be stacked in the form of a hollow cylinder. Further, by proper 70 regulation of the flow of gas through the conduits 12 and 14, a desired pressure may be maintained within the container and any gas of a desired chemical characteristic having a 75 desired effect upon the heated material may be employed.

By my invention, I have provided an improved arrangement of the heating element and charge in a gas-tight container, resulting in the heating of the charge both by radia- 80 tion and convection, thereby increasing the efficiency of the furnace and maintaining a more uniform heat distribution therein.

Modifications may be made in my invention without departing from the spirit and scope thereof, and I desire, therefore, that only such limitations shall be placed thereon as are imposed by the prior art and set forth in the appended claims.

I claim as my invention :

1. In an annealing furnace, the combination with a gas-tight container and an electrical resistor supported therein, of means for stacking work of substantially annular form to be heated in said container around 95 said resistor to effect the heating of the inner portions thereof by direct radiation and of the outer portions thereof by convection.

2. In a heat treating furnace, the combination with a heating chamber and a resistor disposed therein, of means for supporting the work between said resistor and chamber wall to permit the free circulation of furnace chamber gases therearound, whereby the portions of said charge exposed to said resistor are heated by radiation and the portions thereof adjacent the chamber wall are heated by convection.

3. In an annealing furnace, the combination with a gas-tight container, an electrical resistor and a charge to be heated disposed therein, of means for permitting the heating of portions of said charge by direct radiation from said resistor and for permitting the heating of other portions of said charge by convection, said means comprising means for supporting said charge to constitute a hollow cylinder surrounding said resistor and for permitting free circulation of furnace chamber gases upwardly past said resistor and downwardly along the outer surface of said charge.

4. In an annealing furnace, a gas-tight container, an electrical resistor disposed centrally thereof, means for supporting said charge to form a hollow-cylindrical stack about said resistor and in spaced relation to the base of said container, whereby free cir- 125

ulation of furnace chamber gases about said stack axially thereof is effected.

5. In an annealing furnace, a gas-tight container and material in annular form to be annealed stacked therein, an electrical heating element surrounded by said stack, and means for introducing a non-oxidizing

gas into said container to cause a circulation thereof past said heating element and around the outer surface of said stack.

In testimony whereof, I have hereunto subscribed my name this twenty ninth day of October, 1927.

WILLIAM J. DIEDERICHS.
